CLAIM

The ornamental design for a support belt for a headband for ear noise reduction, as shown and described.

DESCRIPTION

FIG. 1 is a support belt for a headband for ear noise reduction showing my new design;

FIG. 2 is a plan view from the opposite side thereof;

FIG. 3 is a side perspective view thereof; and,

FIG. 4 is a perspective view shown curved in use, the headband shown in broken lines is for illustrative purposes only and forms no part of the claimed design.

FIG.1

FIG.2

FIG. 3

FIG. 4
